UNITED STATES PATENT OFFICE.

PUPO PUPESCHI, OF FLORENCE, ITALY.

WIND MUSICAL INSTRUMENT.

SPECIFICATION forming part of Letters Patent No. 512,449, dated January 9, 1894.

Application filed December 30, 1892. Serial No. 456,816. (No model.)

To all whom it may concern:

Be it known that I, PUPO PUPESCHI, a subject of the King of Italy, and a resident of Florence, Italy, have invented certain new and useful Improvements in Musical Wind Instruments, of which the following is a specification.

In all wind instruments such as clarinets, saxophones, oboes, flutes, &c., the short key moved by the little finger of the left hand produces only one fundamental note, usually, called C $\sharp$ or G $\sharp$ on the clarinet; G $\sharp$ on the oboe and the flute. In order to reduce the number of keys and to give greater facility in slurring rapidly certain notes, I have invented a mechanism allowing the key of C $\sharp$ (clarinet), to produce two or three notes, fundamental sounds or relative harmonics, without lifting the finger which makes it act.

In the drawings Figures 1 and 2 represent in elevation my invention as applied to wind instruments.

The mechanism by which I replace the key C $\sharp$ as formerly used, is composed of a lever α and a plate S (Figs. 1 and 2). This plate is not soldered as heretofore to the lever α ; but is connected to the ring D or to one of the rings D, E, F. The ring D has a spring of sufficient strength to lift the plate S which remains open when it does not receive the action of the lever α but in the normal state this lever α presses on the plate S and is fitted with a spring of superior strength to the one on the plate; the action of the lever α closes the plate S.

In order to produce the double or even treble effect required taking the clarinet as an example (Fig. 1) I place the key H above the arm of the lever α . The first action will then be: By pressing the little finger of the left hand on the end of the key H, the lever α swings, leaves the plate S and allows it to open. For the second effect I keep the little finger on the end of the key H and I produce the tone by the usual fingering; for the third effect of the same key H I maintain the little finger of the left hand on the key and produce the tone with the ordinary fingering of the clarinet. It is to be observed that in the three effects which have been described, the plate S, being connected to the ring D,

will close itself naturally by the ordinary fingering required for the production of the second and third effects. I can obtain the same result by placing the key H underneath the lever α . The multiple effect required could also be obtained by the mechanism shown in Fig. 2, in which the key H is combined with the key D and plate 4.

The main feature of my invention consists in enabling the key giving C $\sharp$ to produce two or three fundamental notes with their respective harmonics and consequently facilitating the fingering.

The mechanism can be constructed in many ways. I have taken as example, in the clarinet the key C $\sharp$ serving also to the notes E, B, F $\sharp$; in the oboe the G $\sharp$ key serving also to produce the low D $\sharp$. In the flute the G $\sharp$ could, taken by the long key, be used also to produce the C $\sharp$ from the C $\flat$ or other notes.

My invention can, naturally, be adapted to all instruments having in their construction a similar key to that designed in the clarinet under the name C $\sharp$ in the oboe and the flute under the name of G $\sharp$.

My invention may be adapted to the several types of the clarinet family, the flute, the oboe, the bassoon and the saxophone, &c.

I claim—

In combination in a wind instrument the plate S, the lever α arranged to press said plate down but formed separate therefrom, the ring D under spring tension connected to the plate S and arranged to lift the same when freed from the action of the lever α , the spring for the lever α of greater strength than that for the ring D and the key H for operating the lever α , substantially as described.

In testimony that I claim the foregoing as my invention I have signed my name, in presence of two witnesses, this 1st day of December, 1892.

PUPO PUPESCHI.

Witnesses:

JOHN VAL JACKSON,
SPIRITO BERNARDEZ.
